FLASHLIGHT HOLDING DEVICE

Leonard C. Peterson, Sioux Falls, S. Dak.

Application October 9, 1945, Serial No. 621,330

1 Claim. (Cl. 248—229)

1

This invention relates to a flashlight holding device, and more particularly to an adjustable flashlight holding device for attachment to a car fender.

An object of this invention is to provide an improved flashlight holding device for attachment to a car fender without marring or scratching the fender surface, and which is adjustable to alter the position of the flashlight to provide proper light at night for repairing or changing tires.

Another object of this invention is to provide an improved flashlight holding device for affixing to an automobile fender having a curved clamp to fit curved fenders and having a pad on the clamp so as not to scratch the fender.

It is a further object of this invention to provide for an adjustable car fender flashlight holder having a clamp for attachment to straight edge or round edge fenders without marring the fender surface and having a narrow portion which is bendable to provide for adjustment of the flashlight position without changing the position of the clamp.

Other objects of this invention will appear from the following specification and claim and from the accompanying drawing illustrating the invention, wherein:

Figure 1 is a side elevational view of the flashlight holder clearly showing the fender engaging clamp and the adjustment feature;

Figure 2 is a plan view showing the flashlight engaging fingers, and

Figure 3 is an end elevational view looking towards the flashlight engaging fingers.

Referring to the drawing, the flashlight engaging fingers 1 are wide resilient bars curved to conform to the shape of a flashlight. The outer ends of the fingers have inturned ends 2 which carry hollow rubber rollers 3 for frictionally engaging the flashlight. The inner ends of the fingers merge into flat adjoining portions 4, welded or otherwise connected together, which then flare outwardly, indicated by numeral 5, into spaced apart flat portions 6. Fitted between the portions 6 is a thin wide plate 7 having its outer end rolled on itself to form a tube 8 between the portions 6. An adjustable screw bolt 9 passes through openings in the portions 6 and through the tube 8 and has a wing nut 10 threaded on its end to fasten plate 7 to the portions 6. The end of bolt 9 is flattened slightly at 11 to prevent complete unscrewing of the wing nut, to insure the parts being connected at all times.

The thin plate 7 is curved downwardly and

merges into a thicker portion 12 formed into a U-shaped fender-engaging clamp 12' having the portion 13 thereof curved gradually to conform to the shape of a fender having a curved edge.

5 A pad 14 of rubber or other suitable material completely covers and encases the U-shaped clamp to provide for a protective covering to prevent the marring or scratching of the fender surface. The shorter arm 15 of the clamp 12' is provided with a clamping screw 16 having a finger engaging head 17 for clamping a fender between the screw 16 and the longer arm 18 of the clamp 12'. The end 19 of the screw 16 is slightly flattened to prevent its complete withdrawal and possible loss.

In operation the clamp 12' is slipped over the outer edge of a fender with the screw 16 toward the wheel of the car and with the fender edge between arm 18 and screw 16. In this position the screw 16 is tightened to clamp the device in position. The fingers 1 will extend outwardly from the fender and the flashlight can be inserted between the fingers. The rubber rollers 3 will frictionally engage the flashlight to prevent it from slipping out. If the fender has a curved edge, the clamp 12' is applied so that the curve 13 will lie against the curve of the fender before screw 16 is tightened. In order to adjust the position of the flashlight, it is merely necessary to loosen wing nut 10 slightly and the fingers 1 may be raised or lowered about screw 9 as a pivot. The wing nut 10 is then tightened to hold the fingers 1 and the flashlight in adjusted position. Alternately, or if necessary for further adjustment, an adjustment may be accomplished by bending the thin plate 7 to vary the position of fingers 1 relative to the clamp 12'. The plate 7 is of sufficient strength to prevent accidental bending but is of such ductility to permit forced bending.

40 The flashlight holder may be made of metal or other suitable material, except for rollers 3 and padding 14 which are preferably of rubber.

It is evident that a simple flashlight holder has been devised that is easy to install without scratching the fender and easy to adjust to various positions. The flashlight may be removed without removing the holder. It is also apparent that all parts of the holder are inseparably connected to prevent loss of any of the parts. Also the holder may be easily removed and stored.

While a certain specific embodiment of this invention has been shown it will be understood that various modifications may be made within the spirit of the invention. Therefore no limita-

tions on the invention are intended other than are imposed by the scope of the appended claim.

I claim:

In a portable flashlight bracket comprising a C-clamp with a thumb screw threaded in the end of one of the two arms thereof and directed toward the other arm, a spring band extending from said other arm, and a double-end yoke having the arms at one end thereof straddling the other extending end of the spring band and the other arms at the other end of the yoke being arcuately curved to describe a semi-circle and carrying resilient sleeves or rollers upon the outer ends thereof, the features which include a tubular member integral with the outer extending end of said spring band, a thumb screw extending through the first-mentioned arms of the yoke and said tubular member to secure the yoke to the latter, which include having the latter arms on said yoke divergent and smaller than the arcuate arms thereof, having the spring band

and C-clamp rigidly connected to form a substantially S-shaped unit disposed in a single plane while the arms of the yoke extend in a second plane substantially at right angles to said single plane.

LEONARD C. PETERSON.
